2 SHEETS—SHEET 2.

FIG. 4.

Invéntor:

By his attorney, Nicholas Gouroussos,
Charles S. Godding.

UNITED STATES PATENT OFFICE.

NICHOLAS GOUROUNAS, OF MILLIS, MASSACHUSETTS.

MACHINE FOR FORMING TOE-CAPS.

1,262,325.

Specification of Letters Patent. Patented Apr. 9, 1918.

Application filed October 25, 1917. Serial No. 198,387.

To all whom it may concern:

Be it known that I, NICHOLAS GOUROUNAS, a subject of the King of Greece, residing at Millis, in the county of Norfolk and State 5 of Massachusetts, have invented new and useful Improvements in Machines for Forming Toe-Caps, of which the following is a specification.

This invention relates to a machine for 10 forming toe caps for boots and shoes, the object being to manipulate a flat leather blank in such a manner that it may be shaped to substantially the form which a toe cap assumes in a finished shoe, thus saving, to a great extent, the forming of the toe cap during the operation of lasting a shoe and preventing injury to the toe cap by the lasting operation.

The machine of this invention is particularly adapted to be used in connection with 20 leather which is liable to crack or become otherwise injured during the lasting operation such, for example, as patent leather.

The invention consists in the combination 25 and arrangement of parts set forth in the following specification and particularly pointed out in the claims thereof.

Referring to the drawings:

Figure 1 is a front elevation of my im- 30 proved toe cap forming machine.

Fig. 2 is a detail plan view of the same.

Fig. 3 is a sectional plan taken on line 3-3 of Fig. 1.

Fig. 4 is a plan view of a toe cap blank.

Fig. 5 is a longitudinal section of the toe 35 cap after it has been formed by my improved toe cap forming machine.

Like numerals refer to like parts throughout the several views of the drawings.

In the drawings, 5 is the frame of the machine, 6 is the stationary work support 40 upon which the toe cap 7 is placed. 8 is a movable work support, slidably mounted upon vertical pins 9 and supported upon springs 10 which encircle said pins. 11 is a clamp member provided with ears 12 which have sliding engagement with guides 13 on the frame of the machine. The clamp mem-

ber 11 has racks 14 thereon into which pinions 15 mesh. The pinions 15 are fast 50 to a shaft 16 rotatably mounted in bearings 17 in the frame of the machine and a rotary motion is imparted to said shaft 16 by a handle 18 fast to said shaft.

A cylindrical carrier slide 19 is mounted 55 to slide and rotate in a bearing 20 upon the clamp member 11 and a vertical reciprocating motion is imparted to said slide by a lever 21 which is pivoted at 22 (Fig. 2) to the frame of the machine. A rocking motion is imparted to the lever 21 by a treadle 23 pivoted at 24 to a bracket 25 fast to the frame of the machine and connected by a link 26 to the lever 21. The front end of the lever 21 is bifurcated to engage a collar 65 27 fast to the carrier slide 19 and the bifurcated end of said lever projects into an annular groove 28 in said collar 27.

The carrier slide 19 extends through an arm 29 which is rotatably mounted upon radial arms 30 forming a portion of the frame 70 of the machine. Said arm 29 has a recess 31 therein (Fig. 2) through which extends a pin 32 fast to said arm 29, and mounted upon said pin is a block 33. A link 34 is 75 pivotally connected at 35 to the block 33 at one end and at the other end is pivotally connected at 36 to an arm 37 which is fastened to a shaft 38 rotatably mounted in a bearing 39 on the frame of the machine. 80 The opposite end of the shaft 38 has a pulley 40 fast thereto. A pin 41 is fastened to the arm 29 and extends through a slot 42 in the carrier slide 19.

The arm 29 is free to rock upon the arms 85 30 and is located in a slot 43 provided in said arms, whereby a rocking motion may be imparted to the arm 29 by means of the link 34, but said arm is prevented from moving vertically by reason of its location in 90 the slot 43, so that the carrier slide 19 may be rocked by means of the crank arm 37, link 34 and arm 29, and a vertical reciprocating motion may be imparted to said slide by means of the lever 21, link 26 and treadle 95 23. The link 26 is moved upwardly by

means of the treadle 23 and is moved downwardly by a spring 44, the upper end of which bears against an ear 45 on the frame of the machine and the lower end of which bears against a collar 46 fast to the link 26.

The lower end of the carrier slide 19 has a collar 47 fast thereto which is provided with two radial arms 48 and upon each of said arms is rotatably mounted a former 49.

- 10 The outer ends of said formers are preferably made of a spherical form at 50 and while said formers are free to rotate upon the arms 48, they are prevented from longitudinal movement thereon by means of the 15 screws 51, the inner ends of which project into annular grooves 52 on said radial arms 48.

The general operation of the machine hereinbefore specifically described is as follows: The toe cap blank 7 is placed upon the stationary work-support 6 when the parts of the machine are in the relative positions illustrated in Fig. 1. The clamp member 11 is then depressed by means of 20 the handle 18, rock-shaft 16, pinions 15 and racks 14 until the same contacts with said toe cap blank and holds it firmly against the stationary support 6. The operator then 25 presses his foot upon the treadle and moves 30 the link 26 upwardly, thus rocking the lever 21 and causing the carrier slide 19 to move downwardly carrying with it the formers 49, and a rocking movement is imparted to the slide 19 and the formers 49 by means of 35 the arm 29, link 34, shaft 38 and pulley 40. The formers will thus be brought into contact with the toe cap blank 7 and, rocking to and fro in the arc of a circle, will gradually stretch the toe cap blank 7 and pull it 40 out from between the clamp member 11 and the support 6 until it assumes the position illustrated in dotted lines, Fig. 1. As soon as the toe cap blank 7 bottoms upon the 45 movable work support 8, said movable work-support will yield through the springs 10 upon which it is supported.

When the toe cap blank has been thus formed to the desired extent the operator releases the treadle 23 and the spring 44, 50 acting through the link 26, will cause the front end of the lever 21 to be moved upwardly and the slide 19, together with the formers 49 attached thereto, will also be moved upwardly and away from the blank. 55 The clamp member 11 is then raised to the position illustrated in Fig. 1 by means of the racks 14, pinions 15, rock-shaft 16 and handle 18 to release the toe cap, which is then removed from the machine and the operation repeated.

In Fig. 4 the toe cap blank 7 is illustrated as it appears in plan view before it is submitted to the operation of the machine and

in Fig. 5 the completed toe cap 7' is illustrated after it has been subjected to the operation of the machine.

Having thus described my invention, what I claim and desire by Letters Patent to secure is:

1. A machine for forming toe caps having, in combination, a support for a toe cap, means to clamp said toe cap to said support, a former, a carrier upon which said former is mounted, means adapted to move said former laterally with relation to said toe cap and means to move said former over the surface of said toe cap.

2. A machine for forming toe caps having, in combination, a support for a toe cap, means to clamp said toe cap to said support, a former, a carrier upon which said former is rotatably mounted, means adapted to move said former laterally with relation to said toe cap and means to move said former over the surface of said toe cap.

3. A machine for forming toe caps having, in combination, a support for a toe cap, means to clamp said toe cap to said support, a former, a slide upon which said former is mounted, means adapted to impart a reciprocatory movement to said slide and laterally with relation to said toe cap, and means to impart a rotary movement to said slide, whereby said former may be moved over the surface of said toe cap.

4. A machine for forming toe caps having, in combination, a support for a toe cap, means to clamp said toe cap to said support, a former, a slide upon which said former is rotatably mounted, means adapted to impart a reciprocatory movement to said slide and laterally with relation to said toe cap and means to impart a rocking movement to said slide, whereby said former may be moved alternately in opposite directions over the surface of said toe cap.

5. A machine for forming toe caps having, in combination, a support for a toe cap, means to clamp said toe cap to said support comprising a slidable member, a rack on said slidable member, a pinion engaging said rack and means to impart a rotary motion to said pinion, a former, a carrier upon which said former is mounted, means adapted to move said former laterally with relation to said toe cap and means to move said former over the surface of said toe cap.

6. A machine for forming toe caps having, in combination, a support for a toe cap, means to clamp said toe cap to said support, a former, a slide, an arm projecting laterally from said slide upon which said former is rotatably mounted, means adapted to impart a reciprocatory movement to said slide and laterally with relation to said toe cap and means to impart a rocking movement to

said slide, whereby said former may be moved over the surface of said toe cap.

7. A machine for forming toe caps having, in combination, a stationary support 5 for a toe cap, means to clamp said toe cap to said stationary support, a spring-supported support for said toe cap located beneath said stationary support, a former, a carrier upon which said former is mounted, 10 means adapted to move said former laterally

with relation to said toe cap and means to move said former over the surface of said toe cap.

In testimony whereof I have hereunto set my hand in presence of two subscribing witnesses. 15

NICHOLAS GOUROUNAS.
